APPARATUS FOR STERILIZING CONTAINER PARTS

Godfrey Steerup, Maywood, Ill., assignor to
American Can Company, New York, N. Y., a
corporation of New Jersey

Application September 8, 1930, Serial No. 480,602

7 Claims. (Cl. 250—34)

The present invention relates to an apparatus for electrically sterilizing container parts and has more particular reference to an apparatus where in there is utilized an improved form of electrical arc having highly penetrating and bactericidal characteristics. Such an arc is described and set forth in my pending application on method of producing electrical disruptive discharges, filed in the United States Patent Office, October 11, 1930, Serial No. 488,141.

The principal object of the present invention is the provision of an apparatus for automatically subjecting container parts to the influence of electrical disruptive discharges possessing improved bactericidal characteristics and utilizing such discharges for sterilizing treatment.

An important object of the invention is the provision of an apparatus for continuously conveying container parts through an electrical disruptive discharge zone of improved characteristics for sterilizing the container part by subjecting it to the bombardment of the electrical discharges.

An important object of the invention is the provision of an apparatus for automatically controlling the amount and time interval and the location of electrical discharges used in a sterilizing chamber for sterilizing container parts.

The invention contemplates the maintenance of favorable arcing conditions in an apparatus which continually and automatically treats container parts by subjecting them to the bactericidal action of improved sterilizing electrical discharges, having highly penetrating light rays of short wave lengths of the ultraviolet region and even short wave lengths approaching the X-ray region.

The invention also contemplates the automatic regulation of a constant characteristic of moisture vapor for maintaining leakage paths between spaced electrodes of the apparatus for the purpose of automatically producing improved electrical discharges utilized for impinging against and bombarding container parts conveyed through the apparatus.

Numerous other objects of the invention will be apparent as it is better understood from the following description, which, taken in connection with the accompanying drawings, discloses a preferred embodiment thereof.

Referring to the drawings:—

Figure 1 is a side elevation, partly broken away and partly in section, of an improved sterilization apparatus exemplifying the present invention.

Fig. 2 is a sectional plan view taken substantially along the line 2—2 in Fig. 1.

Fig. 3 is an enlarged transverse sectional view taken along the line 3—3 of Fig. 2.

The apparatus disclosed in the drawings comprises a continuously moving conveyor for advancing a container part, herein illustrated as a container cover, beneath a series of spaced electrodes located in a sterilizing chamber and connected in suitable electrical circuits for producing electrical arcs. Moisture absorbent wicks are disposed between certain of the electrodes for the purpose of providing electrical leakage paths for effecting electrical discharges of intense eruptive quality and discharges having increased spacial limits and highly accentuated penetration characteristics.

The moisture wicks are automatically supplied with the desired amount of moisture to compensate for evaporation and other dispersion of the moisture in the wick caused by the arcing operation, so that a successive flow of electrical disruptive discharges is obtained. The container part after passing through the apparatus and the sterilizing chamber is discharged in sterile condition and may then be used in the packaging of food products or for other purposes. While the sterilizing chamber is largely enclosed it is not sealed from the atmosphere.

The apparatus comprises a horizontal bed 21, 85 having supporting side walls 22 and carried on legs 23. A conveyor, comprising an endless belt 24, moves over pulleys 25 and 26, carried on respective shafts 27 and 28, journaled in bearings 29 and 31 formed in the legs 23. The upper run 90 of the belt 24 passes along the upper surface of the table 21 and within a groove 34 formed therein. This conveyor advances container parts, herein illustrated as can ends or covers 35, along its upper run and from the pulley 25 to the pulley 26. 95

During this travel, the container ends 35 pass through a sterilizing chamber 36 formed interiorly of triangular end walls 37 and 38 mounted upon and supported by the table 21. Intermediate triangular frames 39 are also supported upon the table 21 and these frames, together with the end walls 37 and 38, carry a top rail 40 and support side members 41 and 42 resting in grooves 43 and 44 formed in the table 21 and in grooves 45 and 46 formed in the top rail. These side walls 41 and 42 are preferably made of a transparent material, such as plate glass, which forms an enclosure for the chamber 36 while permitting visual inspection of the interior. The end walls 37 and 38, as well as the intermediate frame 39, 105

are suitably raised along their bottom edges to permit passage of the can ends 35 therebeneath, as illustrated in Fig. 3.

The belt 24 is continually moved by rotation of the pulley 25. For this purpose, the shaft 27 (Figs. 1 and 2) carries a worm gear 51 which meshes with a worm 52 formed on a horizontal drive shaft 53 journaled in bearings 54 projecting outwardly from one of the legs 23. The shaft 53 may be driven in any suitable manner.

A series of horizontally disposed buss bars or heavy wires 61 (three being illustrated) extend in parallel relationship and in a horizontal position adjacent the bottom of the chamber 36.

13 These buss bars are supported in openings formed in the frames 39, the latter being constructed of an electrical non-conducting material, such for example as asbestos. Other buss bars 62 (three being illustrated) are similarly located adjacent

20 the bottom of the chamber and in the same horizontal plane as the bars 61. The different bars 61 and 62 are alternately positioned, each bar 61 being located between and spaced from adjacent bars 62. There results, therefore, as

25 illustrated, six horizontal buss bars in the bottom part of the sterilizing chamber 36, these bars being parallel and being spaced one from another in a horizontal plane.

One end of each bar 61 (Fig. 2) is secured to 30 a connector rod 63 which is bent at right angles to form an arm 64 carried by the wall 37. This wall is also constructed of an electrically non-conductive material, as for example asbestos. In a similar manner, the buss bars 62 are secured to

35 a connector rod 65 which is bent at right angles to form an arm 66 also carried by the wall 37.

The arm 64 is connected to a wire 71 which forms one lead of the secondary circuit of a transformer 72. The opposite end of the winding of 40 this secondary transformer circuit is connected by a wire 73 to the arm 66. The primary circuit of the transformer 72 comprises a wire 74 connected to one end of the wiring of the primary side of the transformer and this wire leads to

45 a circuit breaker or interrupter 75. A wire 77, leading from the interrupter 75, connects through a switch 76 to one side of a source of electrical energy, designated as a generator 78. The opposite side of the generator is connected

50 by a wire 79 to the opposite side of the primary wiring of the transformer 72.

An electrical energy, generated by the generator 78, upon closing of the switch 76 and interrupter 75, flows through the interrupter and 55 the primary winding of the transformer 72 and causes (at certain periods) an induced secondary current, which passes along the bars 61 and 62. The buss bars 61 and 62 constitute electrodes which are spaced so far apart that current will 60 not ordinarily pass across the air gap between them, owing to its relatively high resistance.

Provision is made for completing this secondary circuit of the transformer 72 and producing a spark jump between a bar 61 and an adjacent bar 62 by reducing this resistance, this being accomplished by introducing a leakage path therebetween. The mechanism for obtaining this result comprises a series of wick holders 81 having a center 82 of absorbent material, such as asbestos, 70 which constitutes a wick for the reception of moisture. Each holder 81 rests on top of and extends between a bar 61 and an adjacent bar 62, grooves 83 formed in the lower surface of the holder 81 fitting down over the bars and keeping 75 the holders in proper position (Fig. 3).

These holders 81 are spaced, as illustrated in Fig. 2, to connect different bars 61 and 62 and are located in different longitudinal positions along the bars so that the resulting electrical discharges taking place along the leakage paths will come in various positions, both longitudinally and transversely as regards the travel of the container end 35 as it moves therebeneath with the traveling belt 24.

As soon as a spark is started along its leakage path at one of the holders 81, the moisture present in the arc is evaporated and it is therefore necessary to maintain a constant supply of moisture in the wicks 82 to effect subsequent discharges. This maintaining of the moisture is automatically controlled in a simple manner as illustrated in Figs. 1 and 3.

80 A series of burettes 91 are located in slots 92 cut in one side of the rail 40 and each burette is formed with an annular bead 93 above its center and this bead rests directly on the upper surface of the rail thus forming a support for the burette. Each burette is so positioned as to have its discharge nozzle, designated by the numeral 94, directly above the center of one of the wicks 82. 85 Some of the burettes 91 are bent, as illustrated at 95 in Fig. 3, to properly align their nozzles with their respective wick holders. A valve 96 associated with each burette 91 controls the amount of discharge of a liquid 97 which is contained within the burette. Water has been found to be a suitable liquid for moistening the wick and establishing the leakage paths for the electric arcs.

90 By reason of the distributed positions of the wick holders 81 and the resulting arcs, each container end 35 is subjected to a series of electrical bombardments as it travels beneath the bars 61 and 62. All of the exposed surface of the end is thus treated to the bactericidal actions of the several electrical sparks or arcs and in this way is 95 thoroughly sterilized by the time it reaches the discharge end of the apparatus.

95 The improved electrical spark or arc used in the present invention and produced by the mechanism just described has a swift moving or high velocity stream of electrons and a great quantity of effective energy and highly actinic light rays of different wave lengths. Such a spark or arc being spread out (increased spacially) by the moisture leakage path, is not attended with the intense heat ordinarily present in an electrical spark or arc and is, therefore, more desirable as a sterilizing agent. In other words, it possesses increased effective spacial limits.

100 The sterilized container end 35, when it passes over the pulley 26, falls by gravity off of the belt 24 and through an opening 97 formed in the end of the table 21. It thereupon falls upon a discharge chute 98 supported by a bracket 99 mounted on one of the legs 23 and slides out of the machine. Such a sterilized container end may 105 then be used for any desired purpose.

110 The circuit breakers 75 interrupt the flow of the primary current and, therefore, maintains the explosive effect of the arcs which would otherwise entirely lose their dynamic character, as is well known in the electrical field.

115 It is thought that the invention and many of its attendant advantages will be understood from the foregoing description, and it will be apparent that various changes may be made in the form, construction and arrangement of the parts without departing from the spirit and scope of the invention or sacrificing all of its material advan-

tages, the form hereinbefore described being merely a preferred embodiment thereof.

I claim:—

1. An apparatus for sterilizing container parts, comprising in combination, a conveyor for advancing the container parts through the machine, spaced electrodes mounted adjacent the path of travel of said container parts and connected in an electrical circuit, and means for creating a leakage path near said path of travel and between said electrodes, said means including moisture vapor, whereby a flow of electrical energy passes from one electrode to the other along said leakage path and produces arcs of increased effective spacial limits which impinge on said container parts as they are carried adjacent. 80
2. An apparatus for sterilizing container parts, comprising in combination, a conveyor for advancing the container parts through the machine, spaced electrodes mounted adjacent the path of travel of said container parts and connected in an electrical circuit, and means for providing moisture vapor between said electrodes and near said path of travel to produce a leakage path for the flow of electrical energy therebetween whereby the arcs produced impinge on said container parts for sterilization thereof. 85
3. An apparatus for sterilizing container parts, comprising in combination, a sterilizing chamber, a conveyor advancing the container parts through said sterilizing chamber, a source of electric force, spaced electrodes in the circuit of said force and mounted in said chamber adjacent said conveyor, an electrically non-conducting wick member interposed between said electrodes, and means for forming an electrical leakage path in said wick member whereby an arc is enabled to be produced having increased effective spacial limits which impinges upon and sterilizes the said container part. 90
4. An apparatus for sterilizing container parts, comprising in combination, a sterilizing chamber, a conveyor advancing the container parts through said sterilizing chamber, a source of electric force, spaced electrodes in the circuit of said force and mounted in said chamber adjacent 100
5. An apparatus for sterilizing container parts, comprising the combination of a sterilizing chamber, spaced electrodes located in said chamber, means for creating a leakage path of less electrical resistance than the resistance of the air between said electrodes, said means including moisture vapor, and means for passing electrical energy along said leakage path, whereby the arcs produced impinge on said container parts for sterilization thereof. 105
6. An apparatus for sterilizing container parts, comprising the combination of a sterilizing chamber, a plurality of elongated spaced electrodes located in said chamber, wick members carried on said electrodes, and means for wetting said wick members to provide electrical leakage paths, said wick members being arranged in different longitudinal positions for locating electrical arcs formed by electrical energy passing between said electrodes and across the leakage paths of said wick members. 110
7. An apparatus for sterilizing container parts, comprising the combination of a sterilizing chamber, a plurality of elongated spaced electrodes located in said chamber, wick members carried on said electrodes, means for wetting said wick members to provide electrical leakage paths, said wick members being arranged in different longitudinal positions for locating electrical arcs formed by electrical energy passing between said electrodes and across the leakage paths of said wick members, and means for advancing container parts adjacent to and longitudinally 115
8. An apparatus for sterilizing container parts, comprising in combination, a sterilizing chamber, a conveyor advancing the container parts through said chamber, whereby said container parts are passed through the arcing zones determined by said wick members and thereby sterilized. 120
